UNITED STATES PATENT OFFICE

GERALD J. OLDROYD, OF PHILADELPHIA, PENNSYLVANIA, ASSIGNOR TO LINK-BELT COMPANY, OF CHICAGO, ILLINOIS, A CORPORATION OF ILLINOIS

SKIP HOIST

Application filed October 7, 1929. Serial No. 398,017.

My invention relates to skip hoists and has for one object to provide a new and improved form of skip hoist, either single or double, wherein the discharge point may be adjusted throughout substantially the entire range of movement of the skip, to permit discharge of the contents of the skip at any desired point along the possible travel of the skip.

One object of my invention is to provide an adjustable, movable, skip dumping cam which will, as it is moved along the direction of travel of the skip, cause the skip to dump as soon as it reaches the dumping point or dumping cam, no matter where that may be. Another object is to provide, in co-operation with such dumping cam, automatic means whereby the skip propelling mechanism will cause the skip to stop when it reaches the dumping position and to reverse from that position, wherever that may be. Another object is to provide means associated with such movable dumping cam or cams if there are two used for a balanced pair of skips, means for automatically adjusting the relation between the two skips and the hoisting engine so that changes in the length of excursion of the skip will not interfere with the operation and will permit them to load at the proper point and dump at the proper point. Other objects of my invention will appear from time to time in the specification.

My invention is illustrated more or less diagrammatically in the accompanying drawings, wherein—

Figure 1 is a side elevation and Figure 2 a front elevation of an apparatus arranged to cause the dumping of a single skip at adjustable, variable discharge levels;

Figure 3 is a side elevation and Figure 4 a front elevation of an apparatus arranged to cause variable dumping of a pair of balanced skips;

Figure 5 is a side elevation on an enlarged scale of skip and traveling dumping carriage or switch;

Figure 6 is a front elevation of the device shown in Figure 5.

Figure 7 is a diagrammatic view showing the lower end of the skip hoist with adjustable loading means.

A, A are a plurality of generally upright bucket guides. They may be absolutely vertical, they may be inclined, they may be vertical throughout part of their length and inclined throughout part of their length as the case may be. Mounted for reciprocation along each pair of guides is a bail A¹ having at either end guide-engaging rollers A² A². A³ is a hoisting cable extending upwardly along the guides from the bail over a sheave A⁴ at the top. This hoisting cable is wound about a drum A⁵ on any suitable type of hoisting engine, preferably, though not necessarily, electrically controlled and operated. Extending outwardly from a bail at the bottom is a bracket A⁶. Pivoted on this bracket, and extending inwardly toward and preferably through the bail, and also outwardly away from the bracket, is the skip or bucket A⁷, open at the top in the usual manner. The pivot point of the bucket on the bracket is such that the bucket, when loaded or when emptied, is unbalanced and tends to rotate, as shown in Figures 1 and 3, in a counter-clockwise direction through the bail. A⁸ is a stop or bracket on the bail limiting the counter-clockwise movement of the bucket.

B, B are generally upright traveling carriage guides arranged generally parallel with the bucket guides, no matter what their inclination may be. These traveling carriage guides are located in front of the bucket guides and so spaced with respect to them and the bucket that the up-and-down movement of the bail and bucket is not interfered with by these guides, and so that the bucket may rotate into the dumping position between them. Traveling along these guides is a traveling carriage B¹ supported by means of a cable B² extending over a sheave B³ down to a hoisting engine B⁴. Mounted on this traveling carriage is a discharge hopper B⁵, and associated with the traveling carriage are discharge guides or cam tracks B⁶ for the bucket. The bucket has adjacent its front side and toward the top dumping rollers B⁷ adapted, when the bucket reaches the dumping point, to engage the discharge guides or switch tracks and to be guided thereby outwardly to cause rotation of the bucket into the dumping

position, as shown toward the top of Figure 1. A latch B^8 may be carried by the bail A^1 , tending to hold the bucket against rotation. This latch is adapted to be closed by a spring B^9 which holds it seated on the bucket. The latch is provided with a tail B^{10} adapted to be engaged by a cam B^{11} on the traveling carriage, which cam lifts up the latch as the dumping rollers B^7 approach engagement with the switch track, so as to leave the bucket free to tilt and dump.

The up-and-down movement of the traveling carriage is controlled by means of the hoisting engine associated with it, being manipulated and set by the operator to move the traveling carriage to any desired height and there hold it in position. Wherever that traveling carriage may be, the bucket as it comes up to it will be dumped, and so by this arrangement the bucket may be caused to dump at any point above its loading point within the range of movement of the traveling carriage.

The hoisting engine which operates the bucket is preferably, as above indicated, electrically controlled, and it has the conventional type of electric control apparatus which causes it to go up when loaded, stop in the dumping position, and reverse. There is mounted on the bail a cam C which engages a cam C^1 on the traveling carriage. As the bail goes up and engages this cam it sets the electric control, preferably with a time relay, in operation so that by the time the bail has gone past the traveling carriage, carrying the bucket into the dumping position as shown, the electric control will operate to stop the hoisting engine for a sufficient length of time to permit dumping, and then will reverse to cause the bucket to descend for its next load. Thus the mere movement of the traveling carriage in a direction along the path of the bucket is sufficient to change not merely the point at which dumping takes place but the point at which the stopping and reversal of movement of the skip occurs.

When this device is applied to a pair of balanced skips as distinguished from a single skip, complication enters in, in that, if one bucket stops at an intermediate point without change in the distance along the cable between the two buckets, the other bucket will not have gone down to the loading point. It is necessary, therefore, to provide means for adjusting the relation between the two balanced skips or buckets and the hoisting engine, so that one bucket will always be at the discharge point at the same time that the other bucket is at the loading point, and vice versa, independent of the length of travel of the buckets between the loading and the discharge points. This adjustment is accomplished in the following manner by the mechanism indicated in Figures 3 and 4.

No. 1 bucket is supported by a hoisting

cable D which extends up over a sheave D^1 , thence across to a second fixed sheave D^2 , thence down over a sheave D^3 , thence up over a sheave D^4 , across to another sheave D^5 , and thence down to the hoisting engine D^6 , where this line may be wound about a drum and dead-ended, or be wound about a drum and come out as line D^7 , passing over sheaves D^8 and D^9 to bucket No. 2. As long as sheave D^3 remains in place, movement of the hoisting engine will cause the two buckets to reciprocate in opposite directions. However, any movement of the sheave D^3 with the hoisting engine at rest will tend to raise or lower bucket No. 1, as the case may be. Thus with the parts in the position shown in Figure 4 bucket No. 2 is at the loading position, bucket No. 1 is at the uppermost possible discharge position. If sheave D^3 is raised bucket No. 1 will be lowered an amount equal to twice the shortening of the distance between D^2 and D^3 and D^3 and D^4 . Thus, if the bucket is to dump at the lower point, sheave D^3 will be allowed to move upwardly, thus lowering bucket No. 1 until the desired position is reached, when the hoisting engine may operate to move the two skips in balance, and under such conditions when No. 2 is raised No. 1 goes down, and when No. 1 reaches the level originally occupied by No. 2, No. 2 will have reached the level or dumping point originally occupied by No. 1.

This sheave D^3 is associated with a sheave E . Sheave E being in the bight of the line E^1 , this line E^1 is dead-ended on the structure, extends down around the sheave E , thence up over the sheaves E^2 and E^3 and down to support the movable dump discharge hopper E^4 , which hopper has discharge guides for each of the two buckets. E^5 is a cable connecting the housing of sheaves D^3 and E to the drum of a hoisting engine E^6 , so that by means of this hoisting engine the position of sheaves D^3 and E may both be adjusted so that there is a fixed relation between the length of bucket travel and the position of the dumping hopper and movable dumping guides. Of course, separate means might be used for adjusting the position of the dumping hopper and adjusting the relation between the two skips, but it is simpler and ordinarily preferable to have one means do both. The same kind of electric control for stopping, starting and reversing the hoisting engine is used when two balanced skips are used as when a single skip is used, and, of course, if desired, the weight of the loaded bucket, buckets, hopper or traveling carriage may be counter-balanced by attaching counterweights to the sheaves D^3 or E or onto both of them to relieve the load on the hoisting engines.

I have shown my invention primarily as adapted to a dumping point or dumping means adjustable in position. Manifestly, a

similar modified mechanism might be used, in so far as taking up the slack in the line for the two balanced skips, if, instead of an adjustable dumping point, an adjustable loading point were involved, or it might be possible that both might be adjustable. And, of course, the same is true as regards the single skip—instead of raising and lowering the dumping hopper, the loading hopper might be raised and lowered.

F is a loading hopper having a fixed chute F¹, gate F², and pivoted chute F³. This loading hopper is subject to being raised and lowered along tracks F⁴ by means of a cable 15 F⁵ going over a sheave F⁶ coming down to a hoisting engine F⁷ so that the point of loading as well as the point of discharge may be moved up and down within the range of operation of the device. Carried by this loading hopper are a pair of loading guides F⁸. These guides are of short length as indicated and adapted to guide rollers F⁹ connected by means of stirrups F¹⁰ to the working arm F¹¹ of the gate and chute. As the 20 skip comes down the bottom of it engages the stirrups and forces these rollers down along the guides rotating the gate and pivoted chute from the closed position shown intermediate top and bottom of the figure to 25 the open position at the bottom so that it may discharge into the skip.

Intermediate the top and bottom of this figure is a similar fixed loading hopper, G with fixed chute G¹, combined pivoted gate 35 and chute G², control lever G³, stirrup G⁴ with rollers G⁵. These rollers and stirrup may be, and when they are swung from the full line position into the dotted line position, they are in line with the tracks F⁸ and the 40 skip will cause the upper one of the loading hoppers to function.

Thus if desired there may be two fixed loading hoppers at different levels or there may be a single loading hopper adjustable 45 up and down along the path of the skip or there may be any desired combination of these two. Of course, when the position of the loading hopper is changed no matter how it is done, it becomes necessary to operate 50 the means for changing the relative length of travel of the two skips by the same general type of mechanism as above discussed in connection with the movable dumping point. Of course, the adjustable dumping point and 55 adjustable loading point may be used in co-ordination or separately.

I claim:

1. A hoisting means comprising a generally upright track, a bucket and means for 60 moving it along the track, a dumping receptacle and means adjustable along the track for causing the bucket to dump when in its excursion it reaches the dumping receptacle, automatic control means for the bucket moving means adapted to cause the bucket to stop

at and thereafter reverse its movement away from the dumping receptacle, said means comprising a switch associated with the dumping receptacle and adapted to be actuated by contact with the bucket at the dumping receptacle. 70

2. In combination with a reciprocating material-handling skip of a dumping cam therefor and means for moving it and holding it in predetermined position along the path of travel of the skip, means adapted to be contacted by the skip carried by the dumping means for automatically stopping and reversing skip movement when the skip has reached the dumping means. 75

3. In combination, a pair of balanced skips, means for moving them in opposition one to the other, dumping means associated with the skips adapted to be moved along the path of the skips to vary their travel from loading to dumping points, and means adjustable in consonance with such dumping means for adjusting the relation between said skips to cause one skip to reach the dumping point at the same time as the other reaches the loading point, independent of their length of travel. 80

4. In combination, a pair of balanced skips, means for moving them in opposition one to the other, dumping means associated with the skips adapted to be moved along the path of the skips to vary their travel from loading to dumping points, and excursion adjusting means adjustable in consonance with such dumping means for adjusting the relation between said skips to cause one skip to reach the dumping point at the same time as the other reaches the loading point, independent of their length of travel, said dumping means comprising a movable hopper and dumping cams, the excursion adjusting means comprising means for changing the effective length of the hoisting cable of one of the buckets in consonance with movement of the dumping means. 90

5. A hoisting means comprising a plurality of generally upright tracks, a pair of bucket skips adapted to move along said tracks, a hoisting engine, cables extending from the hoisting engine to both of said skips, the skips being generally balanced, a dumping hopper movable along the path of said skips, means associated with and movable with the dumping hopper for dumping each skip into the hopper when it reaches it, independent of the position of the hopper, means adapted to raise and lower said hopper, sheaves associated with such means adapted to raise and lower one of said skips in consonance with movement of the hopper and independent of normal skip movement to permit simultaneous loading and dumping of the skips at the respective ends of their excursion independent of the length of such excursion. 110

6. In combination two balanced skips, a 115

120

125

- hoisting engine adapted to simultaneously move them in opposite directions, loading and dumping stations for each skip, means for varying the distance between the stations and means independent of and removed from the skip for changing the relation between them and the hoisting engine to cause one skip to be at the dumping and the other at the loading station simultaneously independent of the distance between such stations.
7. In combination two balanced skips, a hoisting engine adapted to simultaneously move them in opposite directions, loading and dumping stations for each skip, means for varying the distance between the stations, means automatically responsive to the adjustment of the distance between the stations for changing the relation between the two skips and the hoisting engine to cause one skip to be at the dumping and the other at the loading station simultaneously independent of the distance between such stations.
8. In combination two balanced skips, a hoisting engine, cables interposed between the hoisting engine and each skip whereby the engine may simultaneously move them in opposite directions, loading and dumping stations for each skip, means for varying the distance between the stations, means independent of and removed from the skip for adjusting the effective length of the cables joining them through the hoisting engine to cause one skip to be at the dumping and the other at the loading station simultaneously independent of the distance between such stations.
9. In combination two balanced skips, a hoisting engine, cables interposed between the hoisting engine and each skip whereby the engine may simultaneously move them in opposite directions, loading and dumping stations for each skip, means for varying the distance between the stations, means for adjusting the effective length of the cables joining the skips through the hoisting engine to cause one skip to be at the dumping and the other at the loading station simultaneously independent of the distance between such stations, said means being automatically responsive to the variation in the distance between the stations.
10. In combination two balanced skips, a hoisting engine adapted to simultaneously move them in opposite directions, a dumping and a loading station for each skip, means for changing the position of the loading station and means for changing the relation between the two skips and the hoisting engine to cause one skip to be at the dumping and the other at the loading station independent of the change of position of the loading station, said means being automatically responsive to change in position of the loading station.
11. In combination two balanced skips, a hoisting engine adapted to simultaneously move them in opposite directions, a dumping and a loading station for each skip, one station being movable, means for changing the position of the movable station and means for changing the relation between the two skips and the hoisting engine to cause one skip to be at the dumping and the other at the loading station independent of the change of position of the movable station, said means being automatically responsive to change in position of the movable station.
12. In combination, two balanced skips, a hoisting engine adapted to simultaneously move them in opposite directions, a dumping and a loading station for each skip, both said stations being movable, means for changing the positions of each movable station, means for changing the relation between the two skips and the hoisting engine to cause one skip to be at the dumping, the other at the loading station, independent of the change of position of either station, said means being automatically responsive to change in station position.
- Signed at Philadelphia, county of Philadelphia and State of Pennsylvania, this 12th day of September, 1929.
